His Attorney.

UNITED STATES PATENT OFFICE

HERMAN J. H. HUBER, OF UPPER DARBY, PENNSYLVANIA, ASSIGNOR TO GENERAL ELECTRIC COMPANY, A CORPORATION OF NEW YORK

CONTACT STRUCTURE

Application filed August 29, 1929. Serial No. 389,303.

My invention relates to switch contact structure and more particularly to a contact structure for use in circuit breakers having comparatively large interrupting capacity.

It is a well known fact that excessive heating may result from poor contact at the contacting surfaces of a switch structure traversed by large currents, and that any arrangement tending to decrease the contact resistance results in increased efficiency of the switch.

It is an object of my invention to provide a structure for decreasing the resistance between contacting surfaces, and to utilize the magnetic forces of the current traversing the switch for further improving contacting engagement between the switch elements.

A further object of my invention is the provision of a brush contact member interposed between a stationary and a movable contact, wherein the mounting of said member is not included in the path traversed by current through the brush member and contacts.

My invention will be more fully set forth in the following description referring to the accompanying drawing, and the features of novelty which characterize my invention will be pointed out with particularity in the claims annexed to and forming a part of this specification.

Referring to the drawing, the single figure thereof illustrates a circuit breaker structure, partly in section, embodying my invention.

Although for the purposes of illustration my invention is shown in connection with an oil circuit breaker of a well known type, it shall be understood that it is not limited thereto but is broadly applicable to any type of switching structure for handling large currents.

Referring to the drawing, a tank or housing 1, containing an insulating fluid 2, as oil, has mounted at its upper part a pair of insulating bushings 3 for supporting and insulating the conductor studs 4 with respect to the housing. The insulating bushings within which the conductor studs are disposed extend within the circuit breaker hous-

ing and beneath the level of the oil body 2, as is well understood in the art.

At the lower end of the conductor studs are mounted members 5 comprising blocks of conducting material, as copper, electrically connected to the conductor studs. Each of the blocks 5 comprises depending flanges, or sides, two sides of which form a support for a transversely extending pivot pin 6 providing a pivotal mounting for a brush contact member 7. The brush contact member 7 is

interposed between block 5 and a movable contact blade or bridging member 9 having an operating rod 10 for effecting opening and closing movement of the switch. Member 7 comprises a plurality of laminæ of conducting material, as copper, clamped together as by riveting or by clamping means 11 intermediate their ends in the form of a sheaf. The sheaf of laminæ may be reinforced by

a member composed of phosphor bronze, for example, disposed along the top lamina. The opposite ends of the sheaf of laminæ are bevelled as illustrated, so as to make good contacting engagement with the plane surfaces of the stationary and movable contacts, comprising the inner face of flange 5a, and the upper face of blade 9, which are disposed substantially at right angles to each other. The contacting tips of the individual laminæ

are preferably formed of silver, since this metal serves to provide better contact between conducting members immersed in an oil body. This is apparently due to the fact that sludge in the oil, which normally tends to increase the resistance at the contacting surfaces, does not impair to such a great extent the electrical contact between silver and another conducting material.

In order to provide better conducting engagement between the opposite ends of the brush member and the stationary and movable contacts, the pivotal mounting 6, which may be loosely fitted if desired, is disposed intermediate the ends of the laminæ and offset with respect to the sheaf so that there may be a limited pivotal movement of the brush member with respect to the contact block 5. As illustrated, this pivotal movement is comparatively slight, and in practice may be of

the order of about 1/32 of an inch, the brush member in its clockwise movement engaging the lower surface of flange 5b, of block 5, this surface serving as a limiting member. It is 5 to be further noted at this point that the offset arrangement of the pivotal mounting permits the current traversing the switch to flow directly through block 5, the individual laminæ of brush 7, and the bridging contact 10 blade 9, thereby eliminating the mounting of the brush from the path traversed by current. The advantage of this arrangement is at once apparent when it is realized that a movable support may often form a comparatively 15 high resistance contact for current passing through the mounting, whereas in the present arrangement, the current divides and passes in parallel through the individual laminæ. Accordingly, the laminæ, if desired, 20 may be insulated, as by enamel, from each other to reduce heating, since it is not necessary that the current pass from one lamina to another as in the case where the laminæ are clamped as a sheaf to the lower end of a 25 conductor stud.

In operation, it sometimes happens that the movable contact blade in travelling to its closed position tends to overtravel this position to a certain extent, thereby setting up 30 stresses in the apparatus depending on the force of the closing movement. In order that such overtravel of the movable blade may be permitted without damage to the contact structure, the sheaf of laminæ has a 35 certain degree of flexibility so that overtravel of the blade 9 simply results in flexing of the brush member and a resultant wiping action along the contacting surfaces of both the stationary and movable contacts. This wiping 40 action furthermore serves to maintain the contacting surfaces clean and to prevent formation of substances thereon tending to increase the contact resistance. Moreover the wiping action between the brush member 45 and contacting surfaces is not limited to a condition wherein the contact blade overtravels its normal position, but occurs to a certain extent upon each closure of the circuit breaker due to the pivotal mounting of the 50 brush contact.

Another factor tending to maintain the brush contact member in good contacting engagement with its cooperating contacting surfaces while the contacts are closed, is 55 the magnetic force of the current traversing the switch. It will be apparent upon inspection of the drawing that the magnetic forces of currents passing through the contact structure tend to force the brush member 60 into wedging engagement along its bevelled edges with the stationary and movable contacts thereby maintaining a very good contact during operation of the circuit breaker. In other words, the magnetic forces, which 65 tend to force the blade 9 downwardly, cause

the opposite ends of the laminæ of each brush to be wedged towards the more constricted area between the stationary and movable contacting surfaces. In case of a large rush of current through the circuit breaker, the brush 70 member tends to be wedged into even firmer engagement with its coacting contacting surfaces, and thereby tends to reduce heating at the contacts by such large currents.

The construction and method of making 75 the brush contact member are comparatively simple in that straight laminæ may be clamped into a sheaf and machined at the ends to produce the bevel desired. Replacement of the brush member is facilitated by 80 the removable pivot pin 6, which may be slid through the sides of member 5, thereby permitting the brush member to be removed.

Although no secondary or arcing contacts 85 have been illustrated or described in connection with my invention, the same being deemed unnecessary for a complete understanding thereof, it shall be understood that the usual types of secondary contacts ordinarily used with inverted brush contacts may 90 be employed.

What I claim as new and desire to secure by Letters Patent of the United States, is:

1. A switch contact structure comprising 95 a pair of stationary contact members each having a plane contacting surface, a relatively movable contact bridging member, a pair of brush members each comprising a plurality of laminæ of conducting material, each brush member interposed between a stationary contact and said movable bridging member whereby each lamina engages at its opposite ends the corresponding plane contacting surface and said bridging member, and means 100 for mounting said brush members so that the magnetic forces of the current traversing said switch force the opposite ends of said laminæ into good contacting engagement with said contact and bridging members.

2. A switching structure comprising a stationary conductor stud having a plane contacting surface, a relatively movable contact member having a contacting surface disposed at an angle to said first-named contacting surface, and a brush member comprising a 110 sheaf of laminæ of conducting material interposed between said stationary and movable contacts within said angle whereby the magnetic forces of the current traversing said switching structure tend to force the 115 opposite ends of said laminæ into good contacting engagement with said contacting surfaces respectively.

3. A switching structure comprising a stationary contact, a relatively movable contact having a contacting surface disposed substantially at right angles to the contacting surface of the stationary contact, and a brush member comprising a sheaf of laminæ of 125 conducting material interposed between said 130

- contacts, the opposite ends of said brush member being bevelled whereby the magnetic forces of the current traversing said switching structure tend to force the opposite ends 5 of the laminæ into individually good contacting engagement with said contacts respectively.
4. A switching structure comprising a stationary contact, a relatively movable contact, 10 and a brush member interposed between said contacts and pivotally mounted on one of them, said brush member comprising a sheaf of laminæ of conducting material whereby current traversing said switching structure 15 divides between said laminæ in passing between said contacts.
5. A switching structure comprising a stationary contact, a relatively movable contact, and a brush member pivotally mounted on 20 said stationary contact, and interposed between the contacting surfaces of said stationary and movable contacts, said brush member comprising a plurality of laminæ of conducting material whose opposite ends directly engage the contacting surfaces of said 25 contacts respectively in the closed circuit position.
6. A circuit breaker structure comprising a stationary conductor stud having a plane 30 contacting surface, a relatively movable contact blade whose contacting surface is disposed substantially at right angles to said first-named contacting surface, and a brush member comprising a sheaf of copper lam- 35 inæ mounted for limited pivotal movement with respect to said conductor stud, said brush member engaging at its opposite ends said contacting surfaces whereby current traversing said structure passes through said 40 laminae between said blade and conductor stud independently of said pivotal mounting.
7. A circuit breaker structure comprising a stationary conductor stud, a relatively movable contact blade, and a resilient brush mem- 45 ber comprising a sheaf of laminæ of conducting material interposed between said stud and blade and mounted for limited pivotal movement on said conductor stud whereby an appreciable overtravel of said contact blade 50 may be permitted during its closing movement, closing movement of said blade serving to force the opposite ends of said brush into good contacting engagement with said stud and blade.
8. In an oil circuit breaker, structure for 55 insuring good electrical contact between the stationary and movable switch members comprising a stationary conductor stud, a movable contact blade, a brush member comprising a sheaf of laminæ of conducting material 60 interposed between said stud and blade, said laminæ provided with silver tips at the opposite ends thereof, and a pivotal mounting for said brush member on said conductor stud, 65 said pivotal mounting disposed intermediate
- the ends of said laminæ and offset with respect thereto whereby current traversing said circuit breaker passes directly through said laminæ independently of said mounting.
9. In circuit breaker apparatus, the combination with stationary and movable contacts, of a brush contact member interposed between the contacts comprising a sheaf of laminæ of conducting material, and means for mounting said member for limited pivotal movement with respect to the stationary contact, the opposite ends of said laminæ each engaging the stationary and movable contacts respectively with limited wiping action 70 upon closure of the movable contact.
10. The combination with an oil circuit breaker comprising a pair of stationary conductor studs and a movable bridging member immersed in an oil body, of contacting structure interposed between said conductor studs 75 and bridging member comprising a contact block secured at the lower end of each conductor stud, and a brush contact comprising a sheaf of laminæ of conducting material pivotally mounted intermediate its ends upon 80 each of said contact blocks, each brush contact being engaged at one end by the bridging member during closing movement thereof whereby the opposite end is forced into good 85 contacting engagement with its correspond- 90 ing contact block.
- In witness whereof, I have hereunto set my hand this 26th day of August, 1929.
